BOTTLE LABELING DEVICE

John C. Robinson, Hutchinson, Kans.

Application November 21, 1938, Serial No. 241,620

4 Claims. (Cl. 216—42)

This invention relates to improvements in bottle labeling devices wherein the various operations, such as bottle moistening, label positioning, and label sealing are manually performed by moving the bottle through various positions with relation to the several units of the device, which are relatively positioned on a common base to insure accuracy and speed of operation.

The principal object of the invention is the provision of a bottle labeling device having means whereby a stack of labels is sustained and guided and whereby the bottle to be labeled is guided to insure a predetermined position relative to the top label of said stack.

A further object of this invention is the provision of adjustable means whereby the relative positions of the bottle and stack of labels may be easily and quickly changed to obtain the desired position of the label on the bottle.

Another object of the present invention is the provision of a bottle labeling device having bottle moistening means, means for sustaining labels and guiding bottles, and label positioning means mounted in convenient relation on a common base whereby the operations of moistening the bottle, positioning the label on the bottle and forming the label about the sides of the bottle, may be easily and quickly accomplished.

Further objects are simplicity and economy of construction, ease and accuracy of operation, and adjustability to various labeling requirements.

The accompanying drawings illustrate the device as arranged for dual labeling whereby the operator may take a bottle in each hand and simultaneously moisten the bottles, position them to pick up and position a label thereon, and to form the labels about the bottles and secure them in this position for a period of time.

In the drawings:

Figure 1 is a front elevation of a bottle labeling device embodying this invention.

Fig. 2 is a plan view of the labeling device partly broken away.

Fig. 3 is a vertical sectional view taken on line III—III of Fig. 1.

Fig. 4 is a plan view of one of the bottle moisteners and a label sustaining and bottle guiding means.

Fig. 5 is an inverted plan view of the mechanism shown in Fig. 4.

Fig. 6 is an elevation of a bottle with the extended label secured thereto; and,

Fig. 7 is a plan view of a bottle with the label secured to its one side, in solid lines, and formed against its opposite sides, in dotted lines.

Throughout the several views, like reference characters designate similar parts, and the numeral 10 is a base having a vertical portion 12, a horizontal section 14 and a downwardly inclined portion 16. This base is preferably made of sheet metal formed as shown, however, it may be flanged or ribbed to prevent undue deflection, if desired.

This base member 10 is secured by means of screws 18, to a table top 20 with the horizontal section positioned below the top surface of the table.

Positioned above the horizontal portion 14 and adjustably secured by means of bolts 22, is an angled bracket 24 which serves as a base for the label positioning means. This bracket 24 may be vertically adjusted by loosening nuts 26 and moving the bracket with the parallel slots 28 moving relative to the stationary bolts 22. After the bracket has been properly positioned, the nuts 26 may be again tightened to secure the parts in fixed relation. Bracket 24 is provided with a series of vertically disposed rods 30 on which is fitted a rectangular partition 32 made of a resilient material, such as sponge rubber.

Adjustable side angles 34 operate in conjunction with the angled bracket structure 24 and are adjusted for horizontal movement by means of bolts 36 mounted in slots 38, which in turn are formed in the vertical base portion 12. Each of the side angles 34 is provided with an outwardly extending arm 40 with an inturned lower lip 42, on which rests a resilient rectangular pad 44.

These pads are normally positioned parallel with the center partition 32 and are adjustable transversely thereto to accommodate bottles of different dimensions. It will be noted by referring to Figs. 1 and 2 that the bottles passing through this label positioning means are slightly embedded in the resilient walls of the partition and side members, thereby insuring a constant pressure against the labels for a sufficient period of time to permit the adhesive to set. The bottles are inserted at the point removed from the table and are delivered to the table so as to form a row of bottles on the table top.

It is very apparent that when a predetermined number of bottles have been positioned on the table top 20 that they may be moved transversely to the line of bottles so as to permit the delivery of two more lines of bottles. This operation may be continued until the table has been completely filled with labeled bottles.

The downwardly inclined portion 16 of the

base is provided at its extremities with bottle moistening means 46. This moistening means comprises a box member 48 having a resilient member 51 mounted therein and extending above the top thereof, to present a groove 50 through which the bottle may be drawn. This resilient member 51 is covered with an absorbent material 52 which is kept moist by the application of water. The groove 50 extends longitudinally of the box and is of a width slightly less than the dimension of the bottle to be moistened.

By drawing the bottle through the groove so that its three sides contact the absorbent material, they will become sufficiently moistened to pick up a label as hereinafter described.

It will be observed that this labeling device is constructed in such a manner as to present identical structures at each side of the center line thereof, in order to make it possible for the operator to take a bottle in each hand and simultaneously perform the various operations, thereby substantially doubling the rate of labeling.

Since the two label sustaining and bottle guiding means 54 are identical in structure, but reversed for the right and lefthand operation, but one of these will be now described.

For convenience this means 54 is positioned on the downwardly inclined base portion 16 intermediate the two bottle moistening means, and comprises a series of parallel standards 56, 58, 60, 62, 64, 66 and 68. Standards 60 and 62 are rigidly attached by means of bolts 10, to the base portion 16, the faces of these standards being disposed in a common plane.

Standards 56 and 66 are mounted for transverse movement in sockets 72 secured by screws 74 to the base member. Standards 56 and 66 are each provided with a guide rod 76 which extends through the socket opening 78. A set screw 80 mounted in socket 72 serves to clamp guide rod against movement. These standards 56 and 66 are in alignment with standards 60 and 62 respectively, and may be moved toward and from said standards to conform to the width of the label L being used.

Standard 58 intermediate standards 56 and 60 is provided with a supporting arm 82 slidably mounted in bracket 84 positioned beneath base portion 16 and secured therein by means of set screw 86. It will be noted that standard 58 extends through a slot 88 formed in the base member. Standard 58 is adjustable lengthwise of the label stack and a similar standard 64 at the opposite end of the stack, is positioned intermediate standards 62 and 66 and is supported on a guide rod 83 which is slidably mounted in socket 90 and adapted to be secured in a fixed position by means of a set screw 92. In order to avoid interference with the other mechanism, guide rod 83 is slightly offset, as clearly shown in Fig. 5.

By means of these six adjustable standards, it is very apparent that labels of different sizes may be properly positioned so as to preclude accidental shifting. As a precaution to prevent more than one label following each bottle from the stack, it will be observed that the faces of the standards 56, 60, 62 and 66 are roughened to present downwardly projecting barbs 94.

The labels to be used with this device are of the standard type with one side covered with an adhesive—said side of the label being always at the top side of the stack so that a moistened bottle pressed thereagainst, will adhere to the label and lift the top label from the stack. In placing the bottle on top of the stack of labels, it be-

comes necessary to provide bottle guiding means to insure a definite and uniform positioning of the label on the bottle. This is accomplished by holding one side of the bottle against the inner edges of standards 62 and 66, as shown in Fig. 4. This makes it possible to center the bottle on the label.

For the purpose of determining the vertical spacing of a label on the bottle, standard 68 is adapted to be moved transversely of the stack 10 of labels so as to limit the downward movement of the bottle. This standard 68 is provided with a bifurcated foot 96, thus presenting a slot 98 through which bolt 100 extends. This bolt is provided with a nut 102 by means of which standard 68 is secured in fixed position relative to the stack of labels. Standard 68 is narrower than the bottle, as clearly shown in Fig. 1, thus making it possible for the operator to maintain his grip at both ends of the bottle during the label positioning operation. Guide rods 76 are flat along one side to receive set screw 80 to maintain standard 66 in a predetermined position.

In the operation of this device, the operator grasps a bottle B between the thumb and forefinger, draws it through slot 50 which has been moistened, thus moistening the three sides of the bottle. This operation is preferably performed with an upward movement of the bottle. On the downward movement of the bottle, the operator positions the bottle against standards 68, 62 and 66 and presses down on the bottle so that it contacts the top label of the stack and adheres thereto so that the label is removed from the stack and is in the position shown on the bottles as illustrated in Figs. 6 and 7. He now forces the bottle between resilient members 44 and 32 of the label positioning means thereby forcing the label against the three sides of the bottle.

Due to the fact that several bottles are constantly positioned in this label positioning means, each bottle will remain therein a sufficient length of time to permit the label to definitely adhere to the bottle. This operation may be carried on simultaneously by the operator with both hands.

It is very evident that the bottle labeling device, as described, will facilitate rapid and accurate labeling of bottles within the smaller range of size.

Having thus described the invention, what is claimed as new and desired to be secured by Letters Patent is:

1. In a bottle labeling device, a slotted base member, a series of standards adapted to be positioned to contact the edges of a label to secure it in position against transverse movement, certain of said standards serving to act as guides to engage one side of said bottle, certain opposed standards of said series being adjustably mounted below said base member to extend through said base slots to engage opposite ends of said label, and an adjustable guide standard adapted to engage the bottom of the bottle.

2. In a bottle labeling device, a series of transversely adjustable, parallel standards adapted to be positioned to contact the edges of a stack of labels to secure them in position, certain of said standards serving as guides to contact a side of the bottle to be labeled, and an adjustable guide standard adapted to engage the bottom of said bottle to determine the vertical position of the label on the bottle.

3. In a bottle labeling device, a series of spaced

apart parallel, transversely adjustable standards adapted to secure a series of superposed labels against lateral movement, the inner face of certain of said standards being roughened to preclude accidental upward movement of the labels; certain of said standards serving as guides for one side of a bottle being labeled; and a standard parallel with said series of standards and transversely adjustable thereto, to engage a portion 10 of the bottom of said bottle to determine the vertical position of the label on the bottle.

4. In a bottle labeling device a series of spaced apart parallel, transversely adjustable standards

adapted to secure a series of superposed labels against lateral movement, the inner face of certain of said standards being roughened to preclude accidental upward movement of the labels; certain of said standards serving as guides for one side of a bottle being labeled; and a standard parallel with said series of standards and transversely adjustable thereto, to engage the one edge portion of the bottom of said bottle to determine the vertical position of the label on 10 the bottle.

JOHN C. ROBINSON.
